(57) **CLAIM**

The ornamental design for a urine collection bag, as shown and described.

DESCRIPTION

FIG. 1 is a front, top perspective view of a urine collection bag, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of detail "9" identified in FIG. 2. The dashed broken lines in the figures illustrate portions of the urine collection bag that form no part of the claimed design. The dash dot dash broken lines in FIGS. 2 and 9 are for the purpose of illustrating the enlarged view indicators and form no part of the claimed design.

1 Claim, 9 Drawing Sheets
